SAMUEL N. WHEATLEY, OF NOBLESVILLE, INDIANA.

TIRE-BOLTING APPLIANCE.

1,165,476.

Specification of Letters Patent. Patented Dec. 28, 1915.

Application filed July 6, 1914. Serial No. 849,277.

To all whom it may concern:

Be it known that I, SAMUEL N. WHEATLEY, a citizen of the United States, residing at Noblesville, in the county of Hamilton and State of Indiana, have invented a new and useful Tire-Bolting Appliance, of which the following is a specification, reference being had to the accompanying drawings and to the letters and figures of reference marked thereon.

10 This invention relates to a power-operated machine or appliance for bolting vehicle tires to the wheels thereof or for removing the nuts from the tire-bolts when repairs are required, the invention having reference more particularly to a tire-bolting appliance that is especially adapted to be applied to a drilling machine and to be driven thereby.

An object of the invention is to provide 20 a tire-bolting machine or appliance that shall be so constructed as to be adapted to be connected to and operated by various styles of drill presses, particularly such as are commonly used in blacksmiths' shops, 25 which machine shall be adapted to be used also in factories for expeditiously turning on and tightening the nuts of the tire-bolts of new vehicle wheels; a further object being to provide a tire-bolting appliance of 30 such construction as to permit vehicle wheels to be readily placed in connection therewith to be supported thereby and so as to obviate the necessity of tediously adjusting the wheel to the appliance or the appliance 35 to the wheel; all to the end that time and labor may be saved so as to result in economy in the necessary operations incidental to the application and removal of wheel tires having retaining bolts.

40 A still further object is to provide a tire-bolting appliance which shall be adaptable for application to the drill presses of different manufacturers, and which may be applied to specially designed power machines 45 and which may in emergency be operated by a hand-power boring machine or a carpenter's brace.

With the above-mentioned and other objects in view, the invention consists in a 50 tire-bolting appliance provided with a bed-plate having means for detachably securing it to various forms of supports, the appliance embracing various novel features of construction whereby the objects of the invention are attained; and the invention consists further in the novel parts, and combi-

nations and arrangements of parts, as hereinafter particularly described and claimed.

Referring to the drawings, Figure 1 is a side elevation of a common type of drill-press adapted to be driven by hand power, minus the drill-table thereof, and having the tire-bolting appliance connected thereto and supporting a vehicle wheel in proper position for tightening or removing a tire-bolt 60 nut. Fig. 2 is a fragmentary section approximately on the line A A in Fig. 1. Fig. 3 is a top plan of the tire-bolting appliance and a fragmentary section of the drill-press to which the appliance is connected. Fig. 70 4 is an inverted plan of an improved socket wrench with which the appliance is provided. Fig. 5 is a section partially broken away on the line B B in Fig. 3. Fig. 6 is a section on the line C C in Fig. 5. Fig. 7 75 is a perspective view of the bed-plate constituting the main portion of the frame of the appliance. Fig. 8 is a perspective view of a part of the frame of the appliance. Fig. 9 is a sectional elevation of a novel gear 80 wheel adapted for carrying the socket wrench.

Similar reference characters on the different figures of the drawings indicate corresponding elements or features of construction herein referred to.

A drill-press to which the improved tire-bolting appliance is adapted to be connected comprises a frame head 1 connected to the top of a column 2 which is vertically arranged and comprises a portion of the frame which may be variously supported, the head 90 rotatably supporting a spindle 3 provided at its lower end with a drill socket 4, a bevel gear wheel 5 being provided for rotating 95 the spindle and driven by another suitably supported bevel gear wheel 6 suitably provided with a hand crank 7. In carrying out the objects of the invention a spindle 8 is provided which is removably secured in the 100 socket 4 and has a squared end portion 9 adapted to be inserted into a socket for driving the tire-bolting appliance. The drill-press includes an arm 10 which is adjustably secured to the column 2 for supporting 105 work under the drill. For the purpose of clearly describing the function of the invention a wheel felly 11 is illustrated and is provided with a tire 12 which is secured to the felly by means of bolts 13, having each 110 a flush head 14 sunk into the tire, and a nut 15 on the end portion of the bolt. In some

cases the arm 10 has an aperture 16 therein adapted to receive bolts for securing work to the arm or for securing a table upon the arm.

The invention as preferably constructed comprises a bed-plate comprising a base portion 17 and a gear frame portion 18, the bed-plate having a plane-faced under side adapted to rest either upon the top of the arm 10 or upon any other flat top support which may be suitable for the purpose. The under side of the base portion has a longitudinally extending recess 19 therein from which a longitudinal slot 20 extends to the top of the base portion, said top having two longitudinally extending guide ribs 21 and 22 on the edge portions thereof. A clamp bolt 23 is provided which has a squared portion 24 adapted to fit slidably in the slot 20, the bolt having a head 25 adapted to enter the recess 19 and engage the under side of the base portion, the bolt being provided also with a nut 26 on its upper end portion. A head block 27 is provided which is adjustably seated upon the base portion and guided between the ribs 21 and 22, a suitable number of filling plates or shims 28 and 29 being placed on opposite sides of the head block, and they may be of different thicknesses. The head block has an aperture 30 through which the bolt 23 extends so that the head block is adjustably secured upon the base portion 17. The head block is provided with horizontal bolts 31 and 32 which extend through the filling plates. Two spring steel clamp plates are provided which have straight portions 33 and 34 respectively that are placed on the outer sides of the filling plates or shims and receive the bolts 31 and 32 whereby all are rigidly secured to the head block 27, the clamp plates comprising curved portions 35 and 36 respectively that embrace the column 2 for securing the appliance to the drill-press. The thickness 45 of the filling plates 28 and 29 usually depends upon the diameter of the column 2 so as to properly space the clamp plates apart to conform to the size of the column. Preferably the clamp plates are provided also 50 with a binding bolt 37 arranged near the column in order to draw and firmly hold the plates to the column. In some cases the bolt 23 obviously may be sufficiently long to extend through the aperture 16 in the arm 10, or a similar bolt may be placed in the aperture so as to extend through the slot 20 whereby to assist the clamp plates in holding the bed-plate securely on the arm 10; or in such case the clamp plates might be 55 dispensed with.

The gear frame portion 18 of the bed-plate has two posts 38 and 39 thereon provided with bolt holes 40 and 41 respectively that extend through the bed plate, and it 60 has also two journal bearings 42 and 43 ar-

ranged between the posts. A frame member 44 is provided which is seated upon the posts and has journal bearings 45 and 46 therein and also bolt holes 47 and 48, one of which receives a bolt 49 that extends through the post 38 and has a flush head 50 set into the under side of the bed-plate, the upper end portion of the bolt having a nut 51 thereon that is seated upon the member 44 for rigidly securing it to the post; the remaining bolt hole of the frame member receiving a bolt 52 which has a flush head 53 let into the top of the member, the bolt extending through the post 39 and having a nut 54 on the lower end portion thereof whereby the member is further secured so as to constitute with the plate portion 18 a suitable gear housing in which a driving gear wheel 55 is arranged and provided with a journal 56 that is rotatably mounted in the portion 18, and a journal 57 that is rotatably mounted in the member 44, the journal 57 projecting through the member 44 and having a squared socket 58 therein to receive the squared portion 9 of the spindle 8 whereby to drive the wheel. A hollow gear wheel 59 is arranged also in the gear housing in mesh with the wheel 55 and it has a hollow journal 60 that is rotatably mounted in the portion 18, there being a bore 61 that extends through the journal and the wheel and also through a journal 62 formed on the opposite side of the wheel from the journal 60, the journal 62 being rotatably mounted in the frame member 44 and is counterbored to form a socket portion 63, the wall of the socket portion having recesses 64 and 65 therein adapted to receive a shank portion 66 of a socket wrench which is provided, the shank portion having an opening 67 therein. The wrench has a head portion 68 that projects beyond the socket portion 63 of the wheel and has a suitable aperture 69 therein that extends to the opening 67 to permit the passage of nuts through the wrench. The aperture 69 may be squared or of other contour to correspond to the square nut commonly used on tire-bolts, or to correspond to the contour of other forms and to various sizes of nuts. The socket wrench is provided with projections 70 and 71 that extend into the recesses 64 and 65 respectively for preventing rotation of the wrench and permitting it to be readily removed and replaced by one of different size or shape.

In order to prevent the bolts 13 from turning in the wheel felly when turning the nuts thereon a bolt holder is provided which comprises a bar or lever 72 and a grip arm 73 which has a curved finger 74 thereon, and also a shoulder 75 formed integrally with the bar and extending laterally from one end thereof, the finger being adapted to embrace the inner portion of the felly while the

5 arm 73 extends adjacent to one side of the felly, the bar 72 having a chisel-edge gouge 76 thereon in proximity to and extending approximately parallel to the arm 73 so as to rest on top side of the head of the tire-bolt.

10 When the bed-plate is secured to the arm 10 of the drill press it is adjusted so that the spindle 8 when connected with the driving wheel 55 shall be in alinement with the spindle 3 of the drill-press and is secured in the socket 4 thereof, and it is evident that the spindle 3 may be elevated so as to draw the spindle 8 away from the socket 58 if desired, but when properly connected therewith the spindle is rotated in the usual manner but is not fed downward as when drilling. When applying a tire the bolts are inserted in place and the nuts placed by hand on the ends of the bolts, after which the felly is hung upon the upper end of the socket wrench so that the wrench receives the nut, and the drill-press being actuated in the proper direction the nut is quickly run on and tightened in the required position. The bolt holder is required only when the bolts are loose in the felly, or in case the nuts are so tight as to cause the bolts to turn. When the bolt holder is required the bar 72 is grasped in the hand of the operator, the curved finger 74 is readily hooked onto the felly and the gouge 76 pressed onto the head of the tire-bolt, the bar 72 being in such position that the operator may grasp the inner side of the felly with his fingers and press down with his thumb over the bar with sufficient force to prevent turning of the bolt. After tightening each nut the wheel is lifted slightly and turned so as to bring another nut into proper position to enter the socket wrench, after which the operation is repeated. When it is desired to remove the nuts in order to make repairs the drill press is operated in the opposite direction so as to unscrew the nuts from the bolts, the nuts falling by gravity through the opening 67 of the wrench and also through the bore 61 of the gear wheel and thus escape without delaying operations.

20 30 35 40 45 50

The nuts obviously may be collected for future use if serviceable.

Having thus described the invention, what is claimed as new is—

1. An improved tire-bolting appliance 55 comprising a bed-plate consisting of a base portion and a gear frame portion, the base portion having two longitudinal guide ribs spaced apart upon the top thereof and having also a longitudinal slot intermediately of the ribs, a head block upon said base portion between said ribs, a bolt extending through said block and said slot and having a head engaging the under side of said base portion, said bolt having a nut thereon upon the top of said block, two clamp plates on the

two opposite vertical sides respectively of said block and projecting beyond the block and the base portion, the plates having oppositely curved terminal portions with the concave faces thereof presented each toward the other, two bolts securing the clamp plates to said block, a gear frame on said gear frame portion, and two intermeshing gear wheels journaled in said gear frame portion and said gear frame and having each a socket therein.

2. An improved tire-bolting appliance comprising a bed-plate consisting of a base portion and a gear frame portion, the base portion being adapted to be fixedly secured horizontally, the gear frame portion having two posts thereon and also two journal bearings between the posts, a frame member fixed on the posts and extending over the gear frame portion parallel thereto, said member having two journal bearings therein, a driving gear wheel having a journal rotatably mounted in one of the bearings of the gear frame portion and also a journal similarly mounted in one of the bearings of said frame member, the last-described journal having a socket in its end, said journals being in the bearings that are the nearer to the base portion of the bed-plate, a hollow gear wheel having a hollow journal rotatably mounted in the remaining one of the bearings of the gear frame portion and also a hollow journal similarly mounted in the remaining one of the bearings of said frame member, the last-described journal having a socket in its end for receiving and turning a bolt nut.

3. In a tire-bolting appliance, the combination of a bed-plate comprising a base portion and a gear frame portion, the base portion having a longitudinal recess in the under side thereof and having also a longitudinal slot extending from the recess through the base portion, said base portion having also two guide ribs on the upper side thereof on opposite sides respectively of the slot, a head block on said base portion between said ribs, a bolt extending through said block and having a head in said recess for adjustably securing the block in place, said bolt having a nut thereon upon the top of said block, two filling plates arranged on opposite sides respectively of said block, two clamp plates arranged on the outer side of the two filling plates respectively and having oppositely curved portions, two bolts securing the clamp plates and the filling plates to said block, a bolt connected to said clamp plates adjacent to said curved portions, and two intermeshing gear wheels journaled in said gear frame portion and having each a socket therein.

105 110 115 120 125 130

4. In a tire-bolting appliance, the combination of a bed-plate comprising a base portion and a gear frame portion, the base

tion being provided with a device for horizontally securing it fixedly, the gear frame portion having two posts thereon and also two journal bearings between the posts, each post having a bolt hole therein extending through the frame portion, a frame member seated upon the two posts and having two journal bearings therein, two bolts in the bolt holes respectively and securing the frame member to the posts, a driving gear wheel having a journal rotatably mounted in one of the bearings of the frame portion and also a journal similarly mounted in one of the bearings of said frame member, the last-described journal having a squared socket in its end, a spindle having a squared

end portion removably inserted in said socket, a hollow gear wheel having a hollow journal rotatably mounted in the remaining one of the bearings of the frame portion and also a hollow journal similarly mounted in the remaining one of the bearings of said frame member, the last-described journal having a socket portion adapted for receiving and turning a bolt nut. 25

In testimony whereof, I affix my signature in presence of two witnesses.
